UNITED STATES PATENT OFFICE.

CHARLES F. POWERS, OF COOSADA STATION, ALABAMA.

DESIGN FOR A CASING FOR SODA-WATER FOUNTAINS.

No. 39,606.

Specification for Design.

Patented Oct. 6, 1908.

Application filed June 6, 1908. Serial No. 437,207. Term of patent 7 years.

To all whom it may concern:

Be it known that I, CHARLES F. POWERS, a citizen of the United States, residing at Coosada Station, in the county of Elmore and State of Alabama, have invented a new, original, and ornamental Design for a Casing for Soda-Water Fountains, of which the following is a specification, reference being had to the accompanying drawing, forming a part thereof.

The figure is an elevation of a casing for a soda water fountain, showing my new design.

I claim—

The ornamental design for a casing for a soda water fountain, as shown.

CHARLES F. POWERS.
